UNITED STATES PATENT OFFICE.

WILLIAM P. RUDKIN, OF BRITTON, OKLAHOMA.

MOTOR-STARTING MECHANISM.

1,135,849.

Specification of Letters Patent. Patented Apr. 13, 1915.

Application filed June 2, 1914. Serial No. 842,540.

To all whom it may concern:

Be it known that I, WILLIAM P. RUDKIN, a citizen of the United States, residing at Britton, in the county of Oklahoma and

5 State of Oklahoma, have invented certain new and useful Improvements in Motor-Starting Mechanisms, of which the following is a specification.

The main object of the present invention 10 is to provide primarily starting mechanism for engines and means in combination therewith for maintaining such mechanism operative at all times, the said means being subject to automatic control when a predetermined abnormal condition is reached, both the starting mechanism and the means aforesaid being independently operable through a common controlling member.

More specifically speaking, I contemplate 20 using in combination with the primary motor of an engine of the explosive type illustrated, an auxiliary motor adapted to be operated by fluid pressure for imparting motion to the primary motor and a compressor for supplying the necessary reserve pressure for the auxiliary motor, clutch mechanisms being interposed between these power devices and operable by a common controlling lever, the shifting of which 25 causes the application of power to the engine or the actuation of the compressor according to whether the fluid pressure is abnormal and whether such pressure is desired for power purposes.

To this end the invention consists of an auxiliary air motor adapted to be actuated by air pressure from a suitable reservoir and to transmit motion to the engine shaft to which it is operably connected through a clutch, an air pump or compressor, for maintaining pressure in the reservoir at proper maximum and which is adapted to be actuated by the engine or more strictly speaking its shaft to which it is also operably connected through a clutch, and a clutch lever connecting the two clutches aforesaid mounted so as to be capable of shifting by means of a controlling lever so as to engage either of the clutches.

50 In addition to the foregoing, the clutch lever is provided with special restraining means whereby when said lever is in a predetermined position to prevent the engagement of both clutches at one time when one only is required for the work to be performed, said restraining means being ren-

dered inoperative to act upon the clutch lever by operation of the controlling lever so as to cause simultaneous disengagement of said clutches.

These and such other objects as may hereinafter appear are attained by the novel construction, combination, and arrangement of parts to be hereinafter specifically described and claimed.

Reference will now be had to the accompanying drawings forming a part of this specification, wherein:

Figure 1 is a side elevation of an embodiment of my invention shown in operative relation to an internal combustion engine. Fig. 2 is a vertical sectional view on the line 2—2 of Fig. 1. Fig. 3 is a vertical sectional view of my apparatus alone. Fig. 4 is a vertical sectional view on the line 4—4 of Fig. 3. Fig. 5 is a detail fragmentary view, partly in section and showing more clearly the arrangement of the clutch lever used in my apparatus. Fig. 6 is an enlarged sectional view of the valve for the distribution of the air pressure. Fig. 7 is an enlarged perspective view of the supporting member for the clutch lever. Fig. 8 is a vertical sectional view on the line 8—8 of Fig. 5; and Fig. 9 is a similar view on the line 9—9 of Fig. 5.

Throughout the following detail description, and on the several figures of the drawings, similar parts are referred to by like reference characters.

Specifically describing the mechanism comprising my invention and referring to the drawings the letter A designates an engine of the internal combustion type and adapted to be operated by the conventional ignition systems well known in this art, said engine being provided with the usual main shaft B and fly-wheel C.

The starting mechanism which forms the subject-matter of my invention consists essentially of a starting motor 1 disposed at a convenient point in advance of the engine A and consisting of a piston 2, the connecting rod 3 and its crank shaft 4. This motor, as will be clear to those skilled in the art to which this invention relates constitutes an auxiliary power device and is adapted to be actuated by fluid pressure supplied from a storage reservoir or tank 5 communicating through the conduit 6 with a conventional type of valve chest 7. The valve of said chest is of the usual sliding type and con-

nected to the eccentric 8 on the crank shaft 4 through the rod 9. The auxiliary motor 1 is adapted to communicate motion to the engine shaft B and for this purpose said shaft or the fly-wheel C is connected to the crank shaft 4 by means of gearing. As illustrated, this gearing consists of the large gear 10 secured to the main engine shaft B and the intermeshing pinion 11 on the inner 10 extremity of the crank shaft 4 of the auxiliary motor. This pinion is formed at one end of a sliding sleeve 12 and said sleeve also includes a clutch element 13 while the co-operating clutch element 14 is fixedly carried by the crank shaft 4.

15 In order to supply fluid pressure to the storage tank 5 I employ a suitable air pump or compressor 15 mounted upon the auxiliary motor 1 by means of the bracket 16 and the plunger 17 of this pump is connected to a crank shaft 18 by means of the connecting rod 19. As shown most clearly in Figs. 1 and 3 of the drawings, the crank shaft 18 is disposed at a convenient point 20 above the fly-wheel C and has slidably mounted thereupon a pinion 20 carried by a sleeve 21 which also includes a clutch element 22 for co-operation with a corresponding clutch element 23 fixedly secured to the 25 crank shaft 18.

30 Disposed vertically intermediate the auxiliary motor 1 and the fly-wheel C is a clutch lever 24 having connection at its opposite ends with the shiftable sleeves 21 and 12, such lever in this manner being a common controlling means for both the pump clutch and the auxiliary motor clutch. The clutch lever 24 as more clearly shown 35 in Fig. 5 is pivotally connected with a supporting bracket 25 projecting rearwardly from the auxiliary motor and as shown in Fig. 7 this bracket is formed with longitudinal lateral slots 26 into which opposing trunnions 27 of the clutch lever project, 40 while said lever itself extends through the vertical longitudinal slot 28 of said bracket. This particular disposition of the clutch lever, it will be obvious, permits of its pivotal movement in the bracket as well as longitudinal movement therealong for reasons 45 to be more clearly set forth hereinafter. The bracket 25, furthermore, is T-shaped in conformation, having abutment arms for the lever designated 29. The lever 24 is connected by means of the rod 30 to a controlling lever 31 arranged at a point convenient to the operator of the device, said controlling lever being pivotally mounted at 32 and provided with a locking segment of the 50 conventional type 33. As will be apparent movement of the controlling lever 31 forwardly or rearwardly will shift the clutch lever 24 on its support so as to enable the engagement and disengagement of the clutch 55 mechanisms for the auxiliary motor and the

compressor in a manner now to be more clearly described.

As will be noted by reference to Figs. 1, 3 and 5, the clutch lever 24 has connected thereto, below its pivot, one end of a spring 34, the other end of said spring being suitably secured to the adjacent motor part in front of the lever. Above the pivot of the clutch lever is arranged a pressure governor 35, the piston plunger 36 of which is 70 connected to said lever at 37, and a spring 35' is interposed between the piston 38 and the casing 39 of the governor 35 which normally exerts a pressure against said piston tending to pull the clutch lever 24 forwardly on its pivot, and moreover the casing 39 of the pressure governor 35 communicates with the storage tank 5 through the conduit 40 so that so long as pressure exists in the tank the equivalent pressure is 75 exerted against the piston 38 of the governor 35 tending to hold said piston against the pressure of the spring 35'. It is to be also borne in mind that the spring 35' is much stronger than the spring 34 connected 80 to the clutch lever below its pivot.

As will be noted in Fig. 1 the pressure tank 5 is provided with a gage 41, and I preferably employ with this apparatus a valve distributor 42 which in this instance 95 is a three-way valve as most clearly shown in Fig. 6. The purpose of the valve as inferred is three-fold and designed to permit of the utilization of the pressure from the tank 5 for various purposes such as the inflation of a tire 43 through the conduit 44, the sounding of the horn 45 connected to said valve through the conduit 46 and it will be obvious that any further application 100 of this pressure is dependent only upon the construction of the valve openings by means of which the pressure is communicated to distributing conduits. The main function of the valve, however, is to admit pressure from the tank to the valve chest 7 105 through the conduit 47 whereby to actuate the auxiliary motor 1 of this starting mechanism.

Assuming, in describing the use and operation of this invention, that there is no 115 pressure existent in the storage tank 5, as for instance, when the starting mechanism is applied initially to the engine, movement of the controlling lever 31 forwardly into the dotted line position designated D will 120 pull the clutch lever along its supporting bracket until its opposing arms abut against the abutment arms 29 of the bracket 25, in which position the clutch mechanisms for the pump and the motor are disengaged. 125 The engine may then be started by its manual cranking means with which they are usually provided but which are omitted from the drawing.

The engine A having been started the con- 130

trolling lever 31 is unlocked and moved rearwardly, shifting the clutch lever 24 forwardly away from its abutments so as to enable the pivotal movement of said clutch lever, and by reason of the greater strength of the spring 35' in the pressure governor 35 the upper end of the clutch lever 24 is moved forwardly until the clutch for the pump 15 is engaged, the lower end of the 5 clutch lever preventing engagement of the clutch for the auxiliary motor, since the spring 34 is not of sufficient strength to counteract the pressure of the spring 35' as above mentioned. In this manner the 10 fluid pressure is supplied to the tank 5 by the pump 15 through the conduit 40 which, is provided with a check-valve 40' adjacent the pump. When the pressure in the tank has reached a predetermined amount, acting 15 upon the piston 38 of the governor, the air pressure will cause the upper end of the clutch lever to be moved rearwardly through the piston plunger 36 connected thereto and thereby disengage the pump clutch. From 20 now on the operation of the engine may be considered to be automatic for with the controlling lever 31 at a position such as just described, the pump clutch will be thrown into engagement so as to communicate power 25 from the main shaft to the pump whenever the pressure in the tank falls below a predetermined amount and such clutch is held out of operative engagement through the pressure governor 35 whenever the pressure 30 is at maximum.

Starting of the engine A after the tank 5 has been charged is accomplished in the following manner: The valve 42 is moved to place the pressure of the tank 5 into communication with the motor 1 through the conduit 47 and the valve chest 7. The lever 31 is moved to a position, such as D of Fig. 1, which immediately throws in the motor clutch while the pump clutch is held out of engagement by the governor 35 as hereinbefore described. Motion having been communicated by the auxiliary motor 1 to the engine shaft B through the gearing 11 and 10, the lever 31 is then moved in an opposite direction to that just mentioned until the clutch is disengaged.

In the event the pressure in the supply tank 5 should become reduced below the predetermined point hereinbefore mentioned, 55 the lever 31 being in locked position, and the pressure governor 35 permits the movement of the clutch lever 24 to cause engagement of the pump clutch, during the engagement of the auxiliary motor clutch, I preferably 60 employ yielding means in the form of a spring 48 interposed in the length of the rod 30 so as to permit movement of the upper end of the clutch lever 24 when the pressure in the governor 35 becomes sufficiently strong to cause such movement.

Breakage of these parts is thus prevented and the necessity of manual movement of the lever 31 eliminated.

It will be perfectly obvious that changes in the construction and arrangement of parts may be readily made without departing from the spirit of the invention and within the scope of the claims hereto appended.

Having thus described my invention what I claim as new is:

1. The combination with a primary motor including a main shaft therefor, of a starting mechanism comprising a fluid pressure auxiliary motor, means for supplying fluid pressure for said auxiliary motor, independent clutch mechanisms intermediate the auxiliary motor and the shaft, the pressure supply means and said shaft, and a common controlling member for said clutch mechanisms, whereby to permit of independent actuation of the shaft by the auxiliary motor to start the primary motor and actuation of the pressure supply means from said shaft.

2. The combination with a primary motor including a main shaft therefor, of a starting mechanism comprising a fluid pressure auxiliary motor, means for supplying fluid pressure for said auxiliary motor, clutch mechanisms intermediate the auxiliary motor and the shaft, the pressure supply means and said shaft, means connecting the clutch mechanism for the pressure supply means with the clutch mechanism of the auxiliary motor, and a controlling member for operating the connecting means to engage and disengage the clutch mechanisms independently of each other.

3. The combination with a primary motor including a main shaft therefor, of a starting mechanism comprising a fluid pressure auxiliary motor, means for supplying fluid pressure for said auxiliary motor, clutch mechanisms intermediate the auxiliary motor and the shaft, the pressure supply means and said shaft, and a controlling member for disengaging one or the other of said clutch mechanisms and maintaining both of said mechanisms out of engaging relations.

4. The combination with a primary motor including a main shaft therefor, of a starting motor, connecting means intermediate the starting motor and the main shaft operable to transmit motion to the latter to start the primary motor, a fluid pressure supply for actuating said starting motor, manually operable means for operating the connecting means aforesaid, a pump for said pressure supply adapted for operable connection to the main shaft and controlled by the manual means aforesaid, and automatic means connected to the manual means for controlling engagement of the pump.

5. The combination with a primary motor

including a main shaft therefor, of a starting motor, connecting means intermediate the starting motor and the main shaft operable to transmit motion to the latter to start the primary motor, a fluid pressure supply for actuating said starting motor, manually operable means for operating the connecting means aforesaid a pump for said pressure supply adapted for operable connection to the main shaft and controlled by the manual means aforesaid, and means connected to the manual means for automatically causing disengagement of the pump when the pressure supply has reached a predetermined amount.

6. The combination with a primary motor including a main shaft therefor, of a starting motor, means intermediate the starting motor and the shaft to communicate motion to the latter, a compressor for supplying pressure for the starting motor, means intermediate the compressor and the shaft for actuating the former, a common controlling member for both said intermediate means, and means for shifting said controlling means to permit of actuation of the shaft by the starting motor or actuation of the compressor from said shaft.

7. The combination with a primary motor including a main shaft therefor, of a starting motor, means intermediate the starting motor and the shaft to communicate motion to the latter, a compressor for supplying pressure for the starting motor, means intermediate the compressor and the shaft for actuating the former, a common controlling member for both said intermediate means, and means movable in one direction to shift the controlling means to provide engagement between the starting motor and the shaft and in the other direction to provide disengagement between these parts.

8. The combination with a primary motor including a main shaft therefor, of a starting motor, means intermediate the starting motor and the shaft to communicate motion to the latter, a compressor for supplying pressure for the starting motor, means intermediate the compressor and the shaft for actuating the former, a common controlling member for both said intermediate means, means movable in one direction to shift the controlling means to provide engagement between the starting motor and the shaft and in the other direction to provide disengagement between these parts, a pressure governor connected to the controlling means and operable by the pressure from the storage means to maintain disengagement between the shaft and the compressor when the starting motor is in driving engagement therewith.

9. The combination with a primary motor including a main shaft therefor, of a starting motor, means intermediate the starting

motor and the shaft to communicate motion to the latter, a compressor for supplying pressure for the starting motor, means intermediate the compressor and the shaft for actuating the former, a common controlling member for both said intermediate means, and a pressure governor connected to the common controlling means to automatically cause engagement between the shaft and the compressor upon reduction of pressure supplied thereby.

10. The combination with a primary motor including a main shaft therefor, of a starting motor, means intermediate the starting motor and the shaft to communicate motion to the latter, a compressor for supplying pressure for the starting motor, means intermediate the compressor and the shaft for actuating the former, a common controlling member for both said intermediate means, a pressure governor connected to the common controlling means to automatically cause engagement between the shaft and the compressor upon reduction of pressure supplied thereby, and means for shifting the controlling means to lock said compressor out of engaging relation with the shaft.

11. The combination with a primary motor including a main shaft therefor, of a starting motor, means intermediate the starting motor and the shaft to communicate motion to the latter, a compressor for supplying pressure for the starting motor, means intermediate the compressor and the shaft for actuating the former, a common controlling member for both said intermediate means, a pressure governor connected to the common controlling means to automatically cause engagement between the shaft and the compressor upon reduction of pressure supplied thereby, and means for shifting the controlling means to simultaneously lock said compressor and starting motor out of engaging relation with the shaft.

12. The combination with a primary motor including a main shaft, of an auxiliary motor, gearing for connecting the auxiliary motor to the shaft, a clutch intermediate the gearing and auxiliary motor, an air pump, gearing arranged to transmit motion from the shaft to the pump, a clutch interposed between the gearing last-mentioned and the pump, and a clutch lever connecting the two clutches aforesaid and constituting a common control for said clutches.

13. The combination with a primary motor including a main shaft, of an auxiliary motor, gearing for connecting the auxiliary motor to the shaft, a clutch intermediate the gearing and auxiliary motor, an air pump, gearing arranged to transmit motion from the shaft to the pump, a clutch interposed between the gearing last-mentioned and the pump, a clutch lever connecting the two clutches aforesaid and constituting a common control for said clutches.

ing a common control for said clutches, and supporting means in which the clutch lever is pivotally mounted intermediate its length whereby to permit of engagement of either 5 of the clutches.

14. The combination with a primary motor including a main shaft, of an auxiliary motor, gearing for connecting the auxiliary motor to the shaft, a clutch intermediate the gearing and auxiliary motor, an air pump, gearing arranged to transmit motion from the shaft to the pump, a clutch interposed between the gearing last-mentioned and the pump, a clutch lever connecting the two clutches aforesaid and constituting a common control for said clutches, supporting means on which said clutch lever is pivotally mounted intermediate its length, said pivot being shiftable on said supporting 20 means, and means for shifting the pivot of said lever.

15. The combination with a primary motor including a main shaft, of an auxiliary motor, gearing for connecting the auxiliary motor to the shaft, a clutch intermediate the gearing and auxiliary motor, an air pump, gearing arranged to transmit motion from the shaft to the pump, a clutch interposed between the gearing last-mentioned and the pump, a clutch lever connecting the two clutches aforesaid and constituting a common control for said clutches, tension means connected to the clutch lever normally tending to cause engagement of the clutch intermediate the auxiliary motor and the shaft, and other tension means connected to the clutch lever and normally tending to prevent engagement of the clutch intermediate the pump and said shaft.

40 16. The combination with a primary motor including a main shaft, of an auxiliary motor, gearing for connecting the auxiliary motor to the shaft, a clutch inter-

mediate the gearing and auxiliary motor, an air pump, gearing arranged to transmit motion from the shaft to the pump, a clutch interposed between the gearing last-mentioned and the pump, a clutch lever connecting the two clutches aforesaid and constituting a common control for said clutches, tension 45 means connected to the clutch lever normally tending to cause engagement of the clutch intermediate the auxiliary motor and the shaft, other tension means connected to the clutch lever and normally tending to prevent engagement of the clutch intermediate the pump and said shaft, and means for locking the clutch lever in a position with the auxiliary motor clutch in engagement and for shifting said lever to disengage the 50 motor clutch and permit engagement of the pump clutch.

17. The combination with a primary motor, of a starting motor for imparting motion to the primary motor, a pressure 55 supply means for actuating the auxiliary motor, comprising a storage tank, an air pump adapted for actuation by the primary motor to supply pressure to said tank, a common controlling member for connecting 60 the auxiliary motor with the primary motor or the primary motor with the pump, and a pressure governor coöperating with the common controlling member automatically operable to maintain disengagement of the 65 primary motor with the pump when the pressure in the tank is at a predetermined amount, and to permit engagement of the pump when the pressure decreases below 70 said predetermined point.

In testimony whereof I affix my signature in presence of two witnesses.

WILLIAM P. RUDKIN.
